INSULATED COOLER

Herbert M. Piker, Wyoming, Ohio, assignor to The Hamilton-Skotch Corporation, Hamilton, Ohio, a corporation of Ohio

Filed Feb. 8, 1962, Ser. No. 68,730

Term of patent 14 years

(Cl. D58—17)

FIG. 1 is a side elevational view of an insulated cooler, showing my new design;

FIG. 2 is an end elevational view thereof;

FIG. 3 is a top plan view thereof;

FIG. 4 is a bottom plan view thereof;

FIG. 5 is a fragmentary, sectional view thereof on line 5—5 on FIG. 2;

FIG. 6 is a fragmentary, sectional view thereof on line 6—6 on FIG. 3; and

FIG. 7 is a fragmentary, sectional view thereof on line 7—7 on FIG. 1.

The side and end not shown are mirror images of the side and end shown respectively.

I claim:

The ornamental design for an insulated cooler, substantially as shown and described.
